UNITED STATES PATENT OFFICE.

JOSEPH ZORECZKY, OF BETHLEHEM, PENNSYLVANIA.

SLUB CATCHER.

Application filed September 17, 1924. Serial No. 738,251.

To all whom it may concern:

Be it known that I, JOSEPH ZORECZKY, a citizen of the United States, residing at Bethlehem, in the county of Northampton 5 and State of Pennsylvania, have invented a new and useful Slub Catcher, of which the following is a specification.

This invention relates to slub catchers commonly employed in connection with 10 winding machines, the primary object of the invention being to provide an adjustable slub catcher constructed of porcelain.

Another important object of the invention is to provide a slub catcher of a novel construction which will possess exceptionally 15 smooth surfaces to reduce the wear on the material passing therethrough to the minimum.

A still further object of the invention is 20 to provide an adjusting means which may be locked in various positions of adjustment by a key fitted for its purpose, thereby eliminating any possibility of unauthorized persons adjusting the slub catcher.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

35 Referring to the drawing:

Figure 1 is a plan view of a slub catcher constructed in accordance with the invention.

40 Figure 2 is a front elevational view thereof.

Figure 3 is a rear elevational view of the slub catcher.

45 Figure 4 is an end elevational view thereof.

Figure 5 is a vertical sectional view taken on line 5—5 of Figure 2.

Figure 6 is a transverse sectional view taken on line 6—6 of Figure 2.

50 Referring to the drawing in detail, the reference character 5 indicates the body portion of the slub catcher which is provided with an elongated opening 6 through which a suitable securing post may be

fastened to secure the slub catcher to a 55 winding machine.

The body portion 5 is formed preferably of porcelain or similar material that may be polished to provide an exceptionally smooth surface over which the material 60 passes to reduce wear on the material to the minimum.

The reference character 7 indicates the usual guide through which the material is passed and as shown, the forward portion 65 of the guide or groove is flared at 8, eliminating rough shoulders or corners at the point of entrance of the material to the guide.

Formed at the rear of the body portion is 70 a cut out portion indicated at 9 which accommodates the porcelain adjustable block 10 which has one end thereof disposed at one end of the guide and adapted to extend across the guide to restrict the width of the 75 guide and adapt it for use in connection with material of various sizes.

In order that the block 10 may be adjusted as described an elongated opening 11 is formed therein, which opening accommodates the bolt 12 that also passes through the body portion 5 to secure the adjustable block 10 in various positions of adjustment. 80

A steel plate indicated at 13 is also provided with an opening to accommodate the 85 bolt 12 which steel plate engages the leather washer 14 positioned on the adjustable block 10 to relieve the porcelain block 10 of undue strain, when the nut 15 which is positioned on the threaded end of the bolt 12 has been 90 properly seated.

From the foregoing it will be obvious that due to this construction, the block 10 may be moved laterally to reduce or increase the width of the guide 7 at the will of the operator. 95

As illustrated by Figure 6 of the drawing, the body portion is formed with a recessed portion to receive the head 16 of the bolt 12, the head being provided with a recess 17 to receive a square tool so that a particular type of tool is necessary in order to remove the bolt or loosen the bolt to accomplish the adjusting thereof, to the end that unauthorized persons may be prevented 100 from making adjustments.

From the foregoing it is believed that the construction and operation of the device will 105

be clearly obvious, and a further detail description as to the use of the device is unnecessary.

I claim:—

- 5 1. A slab catcher comprising a body portion formed of porcelain material and having a cut out portion extending from one edge thereof to provide a thread guide, said body portion having a rear cut out portion, and an adjustable block positioned in the rear cut out portion and adapted to extend into the cut out portion forming the thread guide to restrict the size of the thread guide.
- 10 2. A slab catcher comprising a body portion having a cut out portion extending from one edge thereof to provide a thread guideway, said body portion having a cut out portion formed in the rear surface thereof, an adjustable block of a width equal to 15 the width of the guideway, positioned in
- 20

the last mentioned cut out portion, and means for holding the lock in various positions of adjustment.

3. A slab catcher comprising a body portion having a cut out portion extending from one edge thereof to provide a thread guideway, said body portion having a cut out portion formed in its rear surface and intersecting the first mentioned cut out portion, and an adjustable block in the second 25 mentioned cut out portion for adjusting the size of the thread guideway.

In testimony that I claim the foregoing as my own, I have hereto affixed my signature in the presence of two witnesses.

JOSEPH ZORECZKY.
